UNITED STATES PATENT OFFICE.

JOHN V. CUNNIF, ROBERT E. WILLIAMS, AND JOHN E. HEALY, OF FALL RIVER,
MASSACHUSETTS.

FLUSHING APPARATUS FOR TOILET-BOWLS.

1,110,044.

Specification of Letters Patent.

Patented Sept. 8, 1914.

Application filed July 2, 1913. Serial No. 777,077.

To all whom it may concern:

Be it known that we, JOHN V. CUNNIF, ROBERT E. WILLIAMS, and JOHN E. HEALY, citizens of the United States, residing at 5 Fall River, in the county of Bristol and State of Massachusetts, have invented certain new and useful Improvements in Flushing Apparatus for Toilet-Bowls, of which the following is a specification, reference being had to the accompanying drawings.

This invention relates to new and useful improvements in flushing apparatus for toilet bowls and has for its object to provide an improved device of this character in which 15 the tank proper moves vertically in its fastenings to carry out the operation of the flushing apparatus.

A further object of the invention resides in providing an automatic means for actuating the supply and shut-off valve in the main supply pipe and a still further object resides in providing a device which is simple and durable in construction, inexpensive to manufacture and one which will be very efficient and useful in operation.

With these and other objects in view, the invention consists in the novel features of construction, combination and arrangement of parts as will be hereinafter referred to 30 and more particularly pointed out in the specification and claims.

In the accompanying drawings forming a part of this application, Figure 1 is a vertical section through the flush tank. Fig. 2 is a transverse section therethrough, as seen on line 2—2, Fig. 1. Fig. 3 is a plan view of the bracket with the operating levers thereon. Fig. 4 is a section as seen on line 4—4, Fig. 1, looking in the direction of the 40 arrow. Fig. 5 is a similar view as seen on line 5—5, Fig. 1, looking in the direction of the arrow; and Fig. 6 is an enlarged vertical section through the valve used in connection with the flush tank.

In describing our invention, we shall refer to the drawings in which similar reference characters designate corresponding parts throughout the several views and in which 1 indicates a tank of any desired shape and 50 size, to the under face of which are secured the brackets 2, having depending guide pins or studs 3 formed thereon and additional brackets 4 are provided which are secured to a stationary object, the same slidably receiving said guide pins or studs 3 there-

through. Encircling said guide pins or studs 3, between the top face of the brackets 4 and the brackets 2, are the coil springs 6 which are incased by the slip joints formed of the telescoping tubular sections 5 and 7 60 respectively, carried on the brackets 4 and 2. It will be seen from this construction that the tank 1 is yieldingly supported on the brackets 4. Leading through the top of the tank 1, to a point a short distance above the 65 bottom thereof, is a supply pipe 8, which leads to the main (not shown), and an improved valve 9 is provided in the length of said supply pipe 8, the operation of which will be hereinafter and more particularly 70 described.

The bottom of the tank 1 is provided with an opening 10 around which is formed a valve seat and leading from said opening is a stub pipe section 11 which is telescoped 75 within a pipe section 12. This provides a slip joint between the tank 1 and the pipe section 12 and admits of the contents of the tank being discharged through the pipe 12, at predetermined times. A disk valve 13 is 80 provided, to be seated in the seat surrounding the opening 10 and said valve is carried on the lower end of a tubular shaft 14 which extends upwardly through the tank 1 and beyond the top thereof. The disk valve 13 85 has an opening therein, whereby to permit communication between the tubular shaft 14 and the pipe section 12, and reduced openings 15, provided in the shaft 14 adjacent the upper end thereof, admit of the overflow 90 of water in the tank 1 to exit there-through. A collar 16 is secured on the shaft 14 at a point adjacent the upper end thereof and encircling said shaft between this collar and the top of the tank is a coil spring 17, 95 the normal tendency of which is to force downwardly on said shaft 14 and correspondingly seat the valve 13 over the opening 10.

Mounted on a stationary object above the 100 tank 1, is a supporting bracket 18 and fulcrumed on ears 19 which are carried on said bracket, is a lever 20. This lever is fulcrumed intermediate of its ends and the one end thereof is pivotally connected to the upper end of the tubular shaft 14, which projects above the top of the tank 1. A pull chain 21 is connected to the opposite end of the lever 20, whereby the latter may be operated, when desired.

Mounted on the one end of the supporting bracket 18 is a plate member 22 which is provided with a slot 23, through which the lever 20 is loosely disposed. Pivoted on 5 said plate member is a bell crank lever or the like 24, the one end of which is provided with a latch 25 disposed adjacent the slot 23. A coil spring 26 has one end engaged with the opposite end of the bell crank lever and 10 the opposite end of the coil spring is secured to the plate 22. When the lever 20 is pulled downwardly by the chain 21, so that the end having connection with the shaft 14 is raised, said lever 20 will be raised in the slot 15 23 and held in its raised position by said latch member 25. Thus the valve 13 will remain open when said lever is locked in its raised position, but I have provided a means for automatically releasing the same, which 20 means will be hereinafter described.

Fulcrumed on ears 27 which are also carried on the bracket 18, is an additional lever 28 which has pivotally connected thereto, intermediate of its ends, a shaft or rod 29. 25 This shaft or rod 29 projects upwardly and coöperates with the valve 9 to open and close the same at particular positions of the lever 28 and a coil spring 30, encircling said shaft 29 engages the valve cage and a shoulder on the shaft, so that the normal tendency of the same is to force downwardly on the lever 28. The free end of this lever 28 is adapted to be engaged by the head 31 of an 30 adjusting screw 32, the latter being carried 35 on and projecting upwardly from the top of the tank 1. This lever 28 projects through a slot 33 which is also formed in the plate 22 on the bracket 18. An additional bell crank lever 34 is pivotally mounted on said plate 40 22, the one end of which is designed to form a catch member 35, which engages the lever 28 when the latter is raised. The same is adapted to be held in this position by means 45 of a coil spring 36, which is engaged at its one end with said bell crank lever and at its 50 opposite end with the plate 22. A chain 37 is engaged with the extreme free end of the bell crank lever, opposite that having the latch 35 thereon and is also engaged with the top of the tank 1.

In operation, assuming that the device is completely set up for use and the tank 1 is filled with the proper amount of water, should it be desired to flush the bowl (not 55 shown), the first operation is to draw upon the chain 21. When the chain 21 is pulled, the lever 20 which is swung on its fulcrum point draws upon the shaft 14 and raises the valve 13. The water in the tank 1 then 60 passes outwardly through the opening 10 and through the discharge or flush pipe 12. As the lever 20 is swung on its fulcrum point, the one end of the same will be retained in its raised position by its engagement 65 with the latch member 25, so that the

valve 13 will be retained open until the greater portion of the water within the tank 1 has been exhausted. As the tank 1 becomes emptied and the weight of the same decreases, the springs 6 will tend to raise 70 said tank upwardly. As the tank 1 is raised upwardly, under tension of the springs 6, the head 31 of the adjusting screw 32 will engage the free end of the lever 28 and force the same upwardly. As this lever 28 is 75 forced upwardly, the same will engage the one arm of the bell crank lever 24 and disengage the latch 25 from the lever 20, thereby releasing the latter. At the same time the one end of the lever 20 is raised, the shaft 29 will be raised and the valve 9, in the supply pipe 8 will be opened to permit water from the main to flow to the tank 1. Upon the raising of the lever 28 and the releasing of the lever 20, said lever 28 will 80 also be engaged by the latch member 35 and retained in its raised position, thereby permitting water to flow into the tank 1. When said tank 1 has been filled to a sufficient degree, to overcome the tension of the springs 90 6, the tank will descend and in its descent, will draw upon the chain 37, thereby releasing the engagement of the latch 35 from the lever 28. As the lever 28 is released, the same will be returned to its initial position, under tension of the spring 30 and the valve 9 will thereby be closed. The tank is then 95 ready for an additional flushing, by drawing upon the chain 21.

From the foregoing it will be seen that we 100 have provided a simple, inexpensive and efficient means for carrying out the objects of the invention and while we have particularly described the elements best adapted to perform the functions set forth, it is obvious 105 that various changes in form, proportion and in the minor details of construction may be resorted to without departing from the spirit or sacrificing any of the principles of the invention.

Having thus described this invention, what is claimed is:—

1. In a flushing apparatus, the combination with a receptacle resiliently supported for vertical movement and provided with an 115 inlet valve and an outlet valve, means for opening the outlet valve, means for holding said outlet valve open, a pivoted lever connected to the inlet valve stem, means for releasing said holding means and for raising 120 the lever to open the inlet valve upon upward movement of the receptacle, a trip member adapted to engage said lever to maintain the same in raised position, and a flexible member secured to the trip member 125 and to the receptacle for releasing the trip member upon downward movement of the receptacle.

2. A flushing apparatus comprising a receptacle resiliently mounted for vertical 130

movement and provided with an outlet valve and an inlet valve, a lever pivoted to a fixed object and connected to the outlet valve for actuating the same, means for automatically holding the outlet valve in open position, a lever pivoted to a fixed object and connected to the inlet valve for actuating the same, means for raising the inlet valve lever when the receptacle is raised to open the inlet valve, said inlet valve lever being adapted during its upward movement to release the holding means of the outlet valve lever, a trip member adapted to engage said inlet valve lever when it is raised to hold the same in raised position, and means for releasing the trip member upon downward movement of the receptacle.

3. A flushing apparatus comprising a receptacle resiliently mounted for vertical movement and provided with an inlet valve and with an outlet opening, a vertically movable outlet valve for said opening, a lever pivoted to a fixed object and secured to the outlet valve to raise the same, a pivoted trip member adapted to engage said lever and hold the same in a raised position, a lateral arm on said trip member, a lever pivoted to a fixed object and disposed under said lateral arm, a vertically adjustable member carried by the tank and adapted to engage and raise the last named lever upon upward movement of the tank, whereby the outlet valve will be released, said last named lever being connected to the inlet valve to open it upon the lever being raised, and means for closing the valve.

4. A flushing apparatus comprising a receptacle resiliently mounted for vertical movement and provided with outlet and inlet valves, a lever pivoted to a fixed object and connected to the outlet valve for actuating the same, a lever pivoted to a fixed object and connected to the inlet valve for actuating the same, means for automatically

holding the outlet valve in open position, means for moving the inlet valve lever to open and close the valve when the receptacle is raised or lowered and said lever being adapted, during its movement to release said holding means of the outlet valve lever.

50

5. In a flushing apparatus, an inlet mechanism comprising the combination with a receptacle resiliently supported for vertical movement and an inlet valve, of a pivoted lever secured to the valve stem, means for raising the lever when the receptacle is raised to thus open the valve, a trip member adapted to engage said lever when it is raised and hold it in raised position, and a flexible member secured to the trip member and to the receptacle for releasing the trip member upon downward movement of the receptacle.

55

6. In a flushing apparatus, the combination with a receptacle resiliently supported for vertical movement having an inlet valve, and a lever pivoted to a fixed object, an operative connection between the lever and the inlet valve whereby movement of the lever will actuate the valve, resilient means normally holding the valve closed, a vertically adjustable member secured to the receptacle and adapted to engage the lever to raise it and open the valve when the receptacle rises, a trip member adapted to engage the lever and hold it in raised position, and a flexible connection between the trip member and the receptacle.
